W. McCLAVE,
STOKING MECHANISM FOR FURNACES.
APPLICATION FILED MAR. 22, 1913.

Patented Dec. 28, 1915.

UNITED STATES PATENT OFFICE.

WILLIAM McCCLAVE, OF SCRANTON, PENNSYLVANIA, ASSIGNOR TO McCCLAVE-BROOKS COMPANY, OF SCRANTON, PENNSYLVANIA, A CORPORATION OF PENNSYLVANIA.

STOKING MECHANISM FOR FURNACES.

1,165,792.

Specification of Letters Patent.

Patented Dec. 28, 1915.

Application filed March 22, 1913. Serial No. 756,197.

To all whom it may concern:

Be it known that I, WILLIAM McCCLAVE, a citizen of the United States, and resident of Scranton, in the county of Lackawanna and State of Pennsylvania, have invented certain new and useful Improvements in Stoking Mechanism for Furnaces; and I do hereby declare the following to be a full, clear, and exact description of the same, reference being had to the accompanying drawings, forming part of this specification, and to the figures and letters of reference marked thereon.

This invention relates to mechanism for feeding distributing and handling the fuel, usually grades of more or less comminuted coal, the objects of the invention being to provide apparatus which will be semi-automatic in operation and with which the fuel will be distributed in a manner best calculated to promote combustion and prevent the escape or discharge of any of the solid particles capable of being consumed.

A further object of the invention is to provide a structure in which the fuel on the supporting surface of the grate is readily accessible for being broken up or handled by bars or instruments in the hands of the firemen without disturbing the relationship or operation of the automatic portions of the apparatus.

A further object of the invention is to provide a structure in which the automatic fuel feeding mechanism may be operated with a minimum of power and with mechanical appliances of exceedingly simple character, the whole arrangement being so designed as to materially reduce the cost of manufacture and at the same time permit of the operation of the stoking mechanism by ordinary unskilled labor so as to obtain a maximum efficiency.

Referring to the accompanying drawings.—Figure 1 is a sectional elevation of a portion of a steam boiler furnace embodying a stoking mechanism constructed in accordance with the present invention. Fig. 2 is a detail view showing the preferred construction of the apron angle plate mounted in the wall at the rear end of the grate, and with which the rocking section coöperates.

Like letters of reference in the figures indicate the same parts.

The stoking mechanism of the present invention is shown in connection with a fur-

nace in which the combustion chamber projects in front of the forward end of the boiler with a secondary combustion chamber immediately in rear thereof and beneath the forward end of the boiler, communication with the main combustion chamber being through a suitable opening in an intermediate wall A. The top of the combustion chamber in the particular furnace adopted for illustrating the invention is conveniently 65 in the form of an arch B having passages b therethrough for supplying heated air, but it will be understood that in so far as the present invention is concerned the particular construction of the combustion chamber, 70 aside from the parts immediately associated with the stoking mechanism and to be now described, may be varied indefinitely and made to accord with any known approved or desired practice. 75

The fuel supporting surface or grate proper is preferably composed of fixed grate bars C inclined inwardly and supported at their ends by transverse bearer bars D and D'. Each grate bar has bolted thereto, separate grate sections c provided with horizontally extending shelf-like fuel supporting ledges c', the end faces of which conform to the inclination of the grate bars. At their rear lower ends the grate bars are 85 formed to interlock with the bearer bar D' and at their forward ends they extend through openings in a downwardly extending flange d of the bearer bar D and are retained by transverse pins or similar fastening devices as shown. This type of grate, while preferred, it is obvious may be varied considerably and other known types substituted therefor either having fixed bars or movable bars as in known practice, but in 90 accordance with the present invention the fuel supporting surface of the grate is inclined at an angle which is slightly less than the angle of rest of the fuel to be burned thereon; that is to say, the fuel resting on 95 the grate surface will not normally travel down said surface by gravity alone, but will travel down said surface as a body, if assisted slightly by power or pressure applied thereto, or if the angle of inclination is 100 slightly increased, as for example, by the accumulation of material on the upper portion of the grate, the superposed material will travel by gravity and again restore the angle by accumulation on the lower portion 105 110

115

of the grate, thus maintaining a body of fuel of substantially uniform thickness over the whole grate surface and forming a body which may be advanced bodily down the 5 grate surface by pressure applied to its upper or forward end.

At the forward end of the furnace and above the plane of the grate there is provided a hopper E into which the fuel to be 10 fed is dumped and from which it escapes through a discharge opening controlled by a segmental oscillatory valve or gate F the fuel supporting or controlling portion of which is in the form of a segment of a cylinder, as shown at f. When turned to the 15 position indicated in full lines in Fig. 1, the discharge opening of the hopper is wide open and the valve or gate is in position to close an opening or passageway G through 20 which a bar or instrument may be introduced parallel with the grate surface for manipulating the fuel on said surface should the condition of the fire require such manipulation, or in case a thorough cleaning of 25 the fire is required. The passage G is normally closed by a downwardly swinging door g adapted to be raised when the bar or instrument is introduced and under such conditions the gate or valve F is swung to 30 the position indicated by the dotted line.

The fuel dropping from the hopper E is received by a fuel supporting surface or plate H which forms an upward continuation of the grate surface in the plane of said 35 surface, and working on this fuel receiving surface or plate H is a reciprocatory pusher or feeder K, said pusher or feeder K operating immediately below the passage G and being adapted to advance the fuel dropping 40 from the hopper in a direction which is parallel to the surface of the grate and immediately over said grate, there being no break in the plane of movement such as would cause the fuel to pile up or interfere with 45 its movement as a body down the entire supporting surface.

For operating the pusher or feeder K a simple mechanism well adapted for handling or operating the pushers of a whole battery of furnaces consists of a rock shaft L having an arm l connected with the pusher by a link l' and a second arm m connected by a link m' with a rocking lever m². The rocking lever is connected by a link or connecting rod m³ with an eccentric strap 50 surrounding an eccentric m⁴ on a rotary drive shaft M. By this mechanism the pushers may be reciprocated continuously during the fuel feeding periods and they may be left 55 in continuous operation and the fuel supplied to them controlled by the manipulation of the valves or gates F.

At the lower end of the grate and between 60 said end and the wall A there is arranged a 65 rocking section N preferably journalled to

oscillate in bearings formed in bearer bars O bridged between the bearer bar D' and the wall A, said rocking section embodying rearwardly extending fuel supporting and dumping extensions n and forwardly extending 70 segmental sections n', the movement of the rocking section being controlled by an operating bar or link P extending out to the front of the furnace and at its inner end jointed to a downwardly extending arm p on 75 the rocking section.

For coöperation with the rearwardly extending fuel supporting and dumping portions of the rocking section, the wall A is provided with a segmental downwardly extending apron Q usually mounted on or built into the wall by means of a rearwardly extending top flange or portion Q', and in order to overcome the injurious effects due to the growing of the metal or its expansion 80 and contraction, the apron itself is sub-divided into relatively short sections by slots or openings q, (see Fig. 2) which slots or openings extend back into the top flange Q' a sufficient distance to accomplish the desired 85 end and at the same time leave the rear portion of the flange Q' integral so that the whole apron may be positioned and held in proper relation to the wall and rocking section. To give additional strength the subdivided portions of the apron may be connected with the top portion or flange Q' by 90 bracket webs c².

The rocking section and the apron are so proportioned and arranged that the rocking sections may be oscillated a considerable distance before the rearwardly extending portions n pass beyond the lower edge of the apron when the segmental portions n' extend a considerable distance above the plane of 105 the surface of the grate, whereby without dumping the fuel, ashes, etc., the portion of the mass of fuel at the lower end of the grate may be worked rearwardly and upwardly so as to accumulate a considerable body above 110 the rocking section, where it is in position for the fuel particles not theretofore consumed to be consumed. Air is admitted owing to the fact that the fuel passing down off of the grate will be broken up and elevated above the general plane of the fuel on the grate, and by further or more extended movement of the rocking section it may be dumped into the ash pit for subsequent 115 removal.

The breaking up and pushing back of the fuel passing down off of the grate is an important step in the operation of the mechanism, for, by such manipulation fresh fuel may be fed without dumping the grate, and the complete consumption of the fuel particles is practically assured before the necessity for dumping the same into the ash pit arises. Furthermore when the dumping 125 takes place the body of fuel on the grate 130

is held by resting against the peripheries of the segmental projections.

In the operation of the stoking mechanism, the fuel fed from the hopper and 5 advanced by the pusher progresses over the grate surface in a layer which is successively subjected to the various stages of distillation, coking and consumption progressively, each stage taking place in a portion 10 of the combustion chamber best calculated for the effective combination of the various elements to secure perfect combustion; that is to say, the gaseous elements driven off during the distillation period are at the top 15 of the combustion chamber where they are immediately commingled with highly heated air entering through the arch and the solid fuel particles remaining in the fuel travel down over the grate and are supplied with 20 air from the ash pit in the usual way through the openings in the grate, and through the openings in the rocking section at the lower end of the grate.

Having thus described my invention, what 25 I claim as new and desire to secure by Letters Patent of the United States, is:—

1. In a stoking mechanism for furnaces, the combination with the combustion chamber, grate mounted in an inclined position 30 therein means for supplying fuel to and advancing the same down over the surface of the grate and a fixed rear wall for arresting the progress of the fuel at the lower end of the grate, of a rocking section at the 35 lower end of the grate having a segmental extension forwardly of its axis and a normally substantially horizontal dumping extension in rear of its axis extending into proximity to the rear wall, and means 40 whereby said rocking section may be oscillated to move the segmental extension upwardly, break up the fuel advanced onto the rocking section from the grate and pile the fuel against the rear wall without dropping 45 the same into the ash pit or by a further movement of said rocking section discharge such material into the ash pit.

2. In a stoking mechanism for furnaces, the combination with an inclined grate and 50 means for supplying fuel to and advancing the same down over the surface of said grate, of a reciprocatory rocking section for receiving the material discharged from the grate, and a fixed apron adapted to coöperate with said rocking section having a curved face, said rocking section being provided 55 with an upwardly extending forward portion and a rearwardly substantially flat por-

tion whereby when the forward portion projects upwardly above the plane of the grate 60 surface, the lower rearward portion does not immediately dump the fuel.

3. In a stoking mechanism for furnaces, the combination with a grate mounted in an inclined position with means for supplying 65 fuel to and advancing the same down over the surface of the grate, of a rocking section for receiving the material discharged from the lower edge of the grate, said rocking section having a forwardly extending seg- 70 mental projection movable upwardly past the plane of the surface of the grate, and a rearwardly extending projection, a rear wall, and a fixed apron located on the wall in proximity to the rearwardly extending pro- 75 jection, and having a fuel supporting face substantially conforming to the path of movement of the same whereby the rocking section may be oscillated to move the seg- 80 mental projection above the plane of the surface of the grate and pile the fuel and ashes in proximity to the rear wall without permitting material to be discharged past the rearwardly extending projection.

4. In a stoking mechanism such as de- 85 scribed, the combination with the inclined grate, means for supplying fuel to and advancing the same down over the surface of the grate and a rocking section onto which the material passes from the grate, said rock- 90 ing section having an upwardly extending forward portion and a substantially flat rearward portion, of a fixed apron having a fuel supporting curved face concentric to the arc of movement of the rearward por- 95 tion of the rocking section, said apron having vertical slots in its face whereby the growth of the metal is compensated for.

5. In a stoking mechanism such as de- 100 scribed, the combination with the inclined grate, means for supplying fuel to and advancing the same down over the surface of the grate, and a rocking section onto which the material passes from the lower edge of the grate, of a fixed apron having a fuel sup- 105 porting face curved to substantially conform to the path of movement of the rocking section and subdivided longitudinally of the axis of said section, said apron having a horizontally projecting flange constituting 110 an integral union between its several parts.
